UNITED STATES PATENT OFFICE.

CHARLES M. WILLIAMS, OF QUINCY, WEST VIRGINIA.

TRAIN TOILET DEVICE.

1,166,291.

Specification of Letters Patent. Patented Dec. 28, 1915.

Application filed April 20, 1915. Serial No. 22,607.

To all whom it may concern:

Be it known that I, CHARLES M. WILLIAMS, a citizen of the United States, residing at Quincy, in the county of Kanawha and State of West Virginia, have invented 5 certain new and useful Improvements in Train Toilet Devices; and I do hereby declare the following to be a full, clear, and exact description of the invention, such as 10 will enable others skilled in the art to which it appertains to make and use the same.

This invention relates to train toilet devices, designed for the purpose of providing means to be operated by one of the train 15 hands for flushing the toilet bowl after the train has passed through a city, and one of the principal objects of the invention is to prevent the flushing of toilet bowls in cars during the time they are passing through, 20 cities or thickly populated districts.

The foregoing and other objects may be attained by means of the construction illustrated in the accompanying drawings, in which—

25 Figure 1 is a front elevation of a toilet bowl and means for operating the flushing apparatus made in accordance with this invention, Fig. 2 is a side elevation of the same, Fig. 3 is a vertical sectional view 30 taken through the cylinder, and piston head for operating the dump, Fig. 4 is a front elevation of the compressed air cock, and Fig. 5 is a sectional view through the same.

Referring to the drawings, the numeral 1 35 designates the toilet bowl which may be of the usual or any suitable construction having an extension 2 connected by a suitable base 3 to the floor 4 of the car. Extending through the floor is the discharge portion 5 of the bowl, and an inclined discharge pipe 6 is connected to the underside of the floor, and at the lower end of the discharge pipe 6 is the ordinary dump pan 7, said dump pan being pivoted at 8 and provided with 40 an extending arm 9. The arm 9 is pivotally connected at 10 to a link 11, said link being connected at 12 to a piston rod 13. The piston 45 rod 13 extends through the floor and into a cylinder 14. The cylinder 14 may be located 50 at the side of the bowl 1 or at any suitable point, and comprises a stuffing box 15 through which the piston rod 13 extends, said piston rod having a head 16 connected thereto and provided with suitable packing 55 17. A spiral spring 18 is disposed in the cylinder and bears at one end against the

piston head 16, while the opposite end bears against a detachable cap 19 having a vent hole 20 therein. On the piston rod 13 is a stop 21 which limits the downward movement of the head 16 beyond the opening 22 in the cylinder and connected in the opening 22 is a compressed air pipe 23 which leads through a partition 24 to a separate compartment in the car. Connected to the pipe 23 is an elbow 25 to which a vertical pipe 26 is connected, said pipe leading up through an elbow 27 to a cock or valve 28 having an operating handle 29. From said valve or cock 28 a pipe 30 leads to the compressed air tank or to the air brake system of the train. A steam pipe 31 from any suitable source of supply leads through the floor 4 and encircles the discharge pipe 6, as shown at 32 to prevent freezing of the discharge pipe in cold climates. The coils 33 are connected to the pipe 6 by suitable keepers 33. An overflow aperture 34 is provided near the upper end of the discharge pipe 6.

The operation of the invention may be briefly described as follows: Whenever desired the brakeman may operate the valve or cock 28 to admit compressed air to the cylinder 14 for raising the piston head 16 80 against the tension of the spring 18 to operate the dump pan 7, and when the handle 29 is turned to close the valve, the spring 18 will gradually return the dump pan to its original position. In this way the flushing 90 of the bowl will not occur while the train is passing through a city or a thickly populated district, since the operation of the bowl is entirely within the control of the brakeman or other attendant.

95 It will be obvious that the toilet bowl may be provided with the usual flushing apparatus which can be rendered inoperative by the brakeman when nearing a city.

Various changes may be made in the details of construction without departing from the spirit and scope of the invention as defined in the claims.

What is claimed is:

1. An apparatus for dumping toilet bowls on railway trains having a toilet bowl, an inclined waste pipe connected to said bowl, a dump pan pivoted to the lower part of said waste pipe and extending across the opening thereof, a vertical cylinder secured by the side of said toilet bowl and in vertical alinement with the dump pan, said

cylinder having an inlet aperture, a piston head slidably mounted on said cylinder above said inlet aperture, a piston rod secured to said piston head and extending downwardly, a downwardly inclined arm secured to said dump pan, and a link pivoted to the free end of said arm and to the free end of said piston rod whereby said dump can be operated when said piston head is forced upward.

2. An apparatus for dumping toilet bowls on railway trains, having a toilet bowl, an inclined waste pipe connected to said bowl, a dump pan pivoted to the lower part of said waste pipe and extending across the opening thereof, a vertical cylinder secured by the side of said toilet bowl and in vertical alinement with the dump pan, said cylinder having an inlet aperture,

a piston head slidably mounted in said cylinder above said inlet aperture, a piston rod secured to said piston head and extending downwardly, a downwardly inclined arm secured to said dump pan, a link pivoted to the free end of said arm and to the free end of said piston rod whereby said dump can be operated when said piston head is forced upward, and an enlargement on the upper end of said piston rod, said enlargement being intermediate the piston head and the bottom of the cylinder whereby said piston head is kept above said inlet aperture.

In testimony whereof I affix my signature in presence of two witnesses.

CHARLES M. WILLIAMS.
